UNITED STATES PATENT OFFICE

WILLIAM BARNETT, OF LOS ANGELES, CALIFORNIA

LADDER AND CARRIER THEREFOR

Application filed April 25, 1929. Serial No. 357,999.

This invention appertains to fire ladders and more particularly to a life saving attachment and safety device therefor.

One of the primary objects of my invention is the provision of a novel carriage for association with the usual extension fire ladders, with means for raising the carriage on the ladder, whereby people can be safely lowered down the ladder thereon.

A further object of the invention is the provision of novel guides carried by the carriage for engaging the various sections of the extension ladder, whereby the carriage will be effectively guided during its raising and lowering movement.

A further object of my invention is the provision of novel means for strapping a person in the carriage so as to prevent the falling of the person from the carriage, should the person be overcome by smoke or the like.

A further object of the invention is the provision of novel means for associating a hose with the side of a carriage so that the hose can be effectively brought up the side of a ladder.

A further object of my invention is the provision of a novel gangway which can be detachably associated either with the ladder or the carriage, the gangway being adapted to be used for breaking open a window and for resting on the sill thereof so that persons in the building can gain easy access to the ladder or carriage.

A still further object of the invention is to provide an improved fire ladder attachment of the above character, which will be durable and efficient in use, one that will be simple and easy to manufacture, and one which can be placed upon the market and incorporated with a conventional extension fire ladder at a reasonable cost.

With these and other objects in view, the invention consists in the novel construction, arrangement and formation of parts, as will be hereinafter more specifically described, claimed, and illustrated in the accompanying drawings, in which drawings:

Figure 1 is a fragmentary side elevation of an extension fire ladder showing my improved device incorporated therewith and

in use, the body straps being shown removed from the carriage:

Figure 2 is a front elevation of the same:

Figure 3 is a horizontal section taken on the line 3-3 of Figure 1 looking in the direction of the arrows, the body straps being shown removed:

Figure 4 is a fragmentary vertical section taken on the line 4-4 of Figure 3 looking in the direction of the arrows illustrating the formation of the novel carriage, the body straps being shown removed:

Figure 5 is a detail horizontal section taken on the line 5-5 of Figure 4 illustrating one of my novel guides associated with the carriage and engaging the various extensions of the fire ladder, and

Figure 6 is a fragmentary detail perspective view showing a portion of the rear face of the carriage and one of the guides associated therewith.

Referring to the drawings in detail, wherein similar reference characters designate corresponding parts throughout the several views, the letter A generally indicates an extension fire ladder and B my improved attachment therefor.

The extension fire ladder A can be of any preferred or conventional character and includes a lower section 10 and an upper section 11. As in the usual construction, the upper extension 11 is of a less width than the lower section 10 and the side bars 12 of the section 11 are arranged within and spaced from the side rails 13 of the lower section 10. These sections 10 and 11 are held together in any preferred way.

In accordance with my invention, I provide my novel attachment B which comprises a chair or carriage 15 preferably, but not necessarily, formed of sheet metal. This carriage embodies a rear wall 16 and a bottom wall 17 which is arranged in a horizontal plane, the rear wall 16 being preferably arranged at an angle to the vertical so as to conform to the inclination of the ladder A when the same is placed against the side of a building, and thus the rear wall 16 and the bottom wall 17 are disposed at an obtuse angle. A seat portion 18 is associated with the carriage and

includes a bottom or seat member 19 and a depending front extension 20. The seat can be bolted or otherwise secured to the rear wall 16 while the lower edge of the extension 20 can be bolted or otherwise secured to the bottom wall 17. The space formed by the seat bottom 19 and the extension 20 in connection with the rear wall 16 and the bottom wall 17, can be used for any purpose such as 5 a storage place for hose or the like. It is to be noted that the bottom wall 17 extends beyond the seat so as to form a foot rest and the extreme front edge of this wall can be rolled as at 21 for the reception of a reinforcing 10 and supporting rod 22, the purpose of which will be later described.

Suitable means can be provided for strapping a person in the carriage and thus I provide at spaced points loops 23 for the reception 15 of straps 24 which can extend about the body of the person in the carriage.

In accordance with my invention I provide novel guide means for the carriage and this guide means consists of substantially U-shaped guide members 25 which can be riveted or otherwise secured to the rear face 20 of the back wall 16 adjacent to the corners thereof. These guide members can be formed of sheet metal and can be provided with 25 flanges along their side edges for connection with the rear wall 16. These guides are so arranged that the same will engage the inner faces of the rails 13 of the ladder section 10 when the carriage is on the lower section 30 alone and will ride between the rails 13 of the lower section 10 and the rails 12 of the upper section 11 at the point of connection of said sections and when the carriage rides above the lower section 10, the guides 25 will 35 engage the outer faces of the rails 12 of the upper section 11 alone.

Any desired means can be provided for raising and lowering the carriage on the ladder, but I prefer to provide a cable 26 connected to the upper edge of the rear wall 16 of the carriage and this cable can be trained over a pulley 27 secured to the uppermost rung of the upper ladder section 11. The cable can then be brought down along the inner face of the ladder to the ground so as 50 to constitute a pull member for raising and lowering the carriage.

It is obvious that by this carriage persons can be conveniently lowered down the ladder 55 without danger to the persons or the firemen.

In conjunction with the carriage I also prefer to use a novel gangway 30 which can include side bars 31 and rungs 32. This gangway is preferably formed from iron or 60 steel so as to permit the same to be used for breaking in windows and the like. The forward terminals of the rails 31 can be bifurcated to provide yokes for engaging any one of the rungs of the ladder, as the case 65 may be, or the rod 22 on either side of the

carriage 15. When the gangway is associated with the ladder, the ladder is placed directly in front of the window from which a rescue is to be made and the bifurcated ends 70 33 of the rails 31 are placed over the desired rung and the gangway is then swung down with force against the window for breaking the same in. Persons can then walk from the window to the ladder.

When the gangway is associated with the 75 red 22, the ladder can be placed adjacent the side of the window and the gangway can be swung down with force for breaking in the window and persons can then walk safely from the window along the gangway to the 80 side of the carriage and thence into the carriage.

If preferred, the carriage can be utilized for raising and lowering hoses and to provide for this contingency the sides of the carriage can be provided with hooks or the like 85 34 which can form brackets or supports for the nozzles of the hose.

From the foregoing description, it can be seen that I have provided an exceptionally 90 simple and practical life saving attachment for fire extension ladders.

Changes in details may be made without departing from the spirit or the scope of this invention, but:

What I claim as new is:

The combination with an extension fire ladder including a lower section and an upper section, each section including rails spaced from one another, of an attachment 100 therefor including a carriage, inwardly extending guides carried by the rear face of the carriage adapted to engage the inner faces of the rails of one section of the ladder and the outer faces of the rails of the other 105 section of the ladder and to slide between said faces of the rails of the ladder at the meeting point thereof, and means for raising and lowering said carriage.

In testimony whereof I affix my signature. 110

WILLIAM BARNETT.
